Primary Examiner — Rosemary K Tarcza*Assistant Examiner* — Yolanda Robinson(74) *Attorney, Agent, or Firm* — Kim Winston LLP(57) **CLAIM**

The ornamental design for a stripped screw extractor, as shown and described.

DESCRIPTION

FIG. 1 is a perspective view of a stripped screw extractor in accordance with the new design;

FIG. 2 is a front view of the stripped screw extractor;

FIG. 3 is a rear view of the stripped screw extractor;

FIG. 4 is a top view of the stripped screw extractor;

FIG. 5 is a bottom side view of the stripped screw extractor;

FIG. 6 is a left side view of the stripped screw extractor; and,

FIG. 7 is a right side view of the stripped screw extractor. The broken lines in FIGS. 1-7 illustrate portions of the stripped screw extractor which form no part of the claimed design.

1 Claim, 4 Drawing Sheets(56)
